TOOTHBRUSH AND CUP COMBINATION

Lindsey Taylor, 4150 Mockingbird Lane, Dallas, Tex.

Filed June 23, 1964, Ser. No. 80,524

Term of patent 14 years

(Cl. D9—2)

FIG. 1

FIG. 2

FIG. 3

FIG. 4

FIG. 1 is an end perspective view of a toothbrush and cup combination showing my new design;

FIG. 2 is a rear elevational view thereof;

FIG. 3 is a front elevational view thereof; and

FIG. 4 is a side perspective view thereof.

The opposite side not shown has substantially the same appearance as the side shown.

I claim:

The ornamental design for a toothbrush and cup combination, as shown and described.
